UNITED STATES PATENT OFFICE.

JOHN B. HARDY, OF CHESTER, CONNECTICUT.

DESIGN FOR A FLEXIBLE-CORD-TIP COUPLING.

SPECIFICATION forming part of Design No. 30,255, dated February 21, 1899.

Application filed January 16, 1899. Serial No. 702,373. Term of patent 7 years.

To all whom it may concern:

Be it known that I, JOHN B. HARDY, a citizen of the United States, residing at Chester, in the county of Middlesex and State of Connecticut, have invented a new and original Design for a Flexible-Cord-Tip Coupling, of which the following is a specification.

Referring to the accompanying drawings, which form a part of this specification, Figure 1 is a side elevation of a coupling for the end of an elastic, cotton, leather, or other flexible cord, showing the new design. Fig. 2 is a plan of this cord-tip, showing the transverse outline of the design; and Fig. 3 is a longitudinal section of the same, showing the interior configuration of the design.

As shown in the drawings, the leading or material feature of the design consists in a

series of rounded ribs 1, with intermediate grooves or corrugations 2 arranged spirally on the exterior and interior of a hollow tapering or frusto-conical body, so as to produce the appearance of a tapering spiral coil, with an open loop or hook 3 extending centrally from the larger end of the body, the open loop or hook being contracted between the body and the outer end, as illustrated at 4 in Fig. 1.

Having described my invention, what I claim as new, and desire to secure by Letters Patent, is—

The design for a flexible-cord-tip coupling as herein shown and described.

JOHN B. HARDY.
